UNITED STATES PATENT OFFICE.

CLIFFORD C. FLETCHER, OF HARRISBURG, PENNSYLVANIA.

DESIGN FOR A TAG.

43,216.

Specification for Design.

Patented Nov. 5, 1912.

Application filed September 10, 1912. Serial No. 719,689. Term of patent 3½ years.

To all whom it may concern:

Be it known that I, CLIFFORD C. FLETCHER, a citizen of the United States, residing at Harrisburg, in the county of Dauphin and State of Pennsylvania, have invented a new, original, and ornamental Design for Tags, of which the following is a specification, reference being had to the accompanying drawing, forming part thereof.

The figure is a plan view of a tag, showing my new design.

I claim:—

The ornamental design for a tag, as shown.

CLIFFORD C. FLETCHER.

Witnesses:

ELIZA LINGLE,

M. FLETCHER.
